FIG. 4.

FIG. 5.

Inventor

Jerry. E. Wesolowski.

UNITED STATES PATENT OFFICE.

JERRY E. WESOLOWSKI, OF BUFFALO, NEW YORK.

AUTOMATIC SIGNAL FOR RAILROAD CROSSINGS.

Application filed July 17, 1923. Serial No. 652,086.

To all whom it may concern:

Be it known that I, JERRY E. WESOLOWSKI, a citizen of the United States, residing at Buffalo, in the county of Erie and State 5 of New York, have invented certain new and useful Improvements in Automatic Signals for Railroad Crossings, of which the following is a specification.

This invention relates to automatic rail- 10 road signals for warning the drivers of approaching vehicles when a railroad train is approaching a grade crossing.

The primary object of the invention is to provide an electrically operated signal 15 which will automatically be operated by the wheels of the locomotive as the train approaches the grade crossing so that a warning signal will be energized to be observed by the drivers of approaching 20 vehicles, whereby the drivers will have ample time to stop the vehicle before reaching the railroad crossing.

Other objects of the invention will appear 25 upon consideration of the following detailed description and accompanying drawings in which,

Figure 1 is a plan view of the signal 30 diagram for operating the signal,

Figure 2 is a section through the operating switch,

Figure 3 is a cross section through the railroad rail showing the switch operating element,

Figure 4 is a front elevation of the signal 35 box, and

Figure 5 is a cross section through the same.

Referring to the drawings by numerals, 40 the railway rails 1 and 2, arranged in pairs, indicate the rails over which the train travels in the direction indicated by the arrows. One of the rails in each pair is provided with a switch box 3 which should be a considerable distance from the grade crossing 45 so that the signal will be energized when the train is far enough away from the grade crossing to give ample warning to the driver of an approaching vehicle.

The switch box or housing 3 is in the 50 form of a housing within which is mounted a switch contact 4 attached to the plate 5 which is supported on coil springs 6 in the bottom of the housing, and to which the wire 7 is connected in the electric circuit

which is provided with the battery 8 for 55 supplying the required energy.

The top of the housing 3 is provided with an opening 9 within which is mounted a movable switch contact 10 which is in vertical alignment with the switch contact 4 and which is provided at its lower end with a contact plate 11 adapted to engage the contact member 4. A coil spring 12 is interposed between the head of the member 10 and guide brackets 13 within the housing, 60 so that upward movement is normally imparted to the movable switch member 10 whereby it will be held in open position. A stop flange 14 is attached to the head of the movable contact member 10 whereby 65 downward movement will be limited. The movable switch member 10 is connected to the electric wiring by the conductor 15 which leads to the electric circuit.

One of these switch elements will be 70 provided in each pair of rails as indicated at 17 and 18 in Figure 1, so that the switch will be operated when a train approaches from either direction.

Mounted adjacent the crossing is the 75 electric signal which consists of signal casings 19 having glass panels 20 in opposite sides thereof and provided on its disc with an electric light 21 which is connected in circuit with the corresponding switches 80 17 or 18 according to which of the signals is to be energized. The panels 20 are prominently inscribed with words of warning to indicate to the drivers of approaching vehicles that they must take warning of a 85 train, and this inscription may be as conspicuous as desired, as shown to advantage 90 in Figure 4 of the drawings.

As a train approaches the grade crossing, 95 the flange of the wheel of the locomotive will engage the switch element 10 and depress the same until it is in contact with the switch element 4, thus closing the circuit between the wires 7 and 15, whereby the signal lamp 21 within the signal housing 100 will be energized to illuminate the glass panels, whereby the driver of the vehicle may be promptly warned of the approach of the train. Obviously, a bell or other audible signal may be included in the circuit 105 so that the bell may be energized during the daytime if desired.

Minor changes may be made in the details

of construction without departing from the spirit of the invention or the scope of the claims hereunto appended.

What I claim as new and desire to secure by Letters Patent is:

1. An automatic signal for railroad crossings comprising, in combination with railway rails, a switch housing mounted adjacent one of the rails in each pair, a resilient contact switch member arranged in the switch housing, springs supporting the resilient switch member in a slightly elevated position, a vertically movable switch member mounted above the resilient switch member, a supporting bracket, a coil spring interposed between the supporting bracket and the head of the said movable switch member, a stop plate carried by the movable switch member to limit the downward movement of the switch member in the housing when the two switch members are in engagement, such movable switch member being in close proximity to the head of one of the rails whereby it will be engaged by the flange of one of the wheels of the train, an electric circuit having conductors connected to the said switch members, a signal element arranged adjacent the grade crossing at opposite sides of the said rails and including a signal element adapted to be electrically energized when the two switch elements are in engagement to close the circuit.
2. An automatic signal for railroad crossings comprising, in combination with railway rails, a switch housing mounted

adjacent one of the rails in each pair, a resilient contact switch member arranged in the switch housing, springs supporting the resilient switch member in a slightly elevated position, a vertically movable switch member mounted above the resilient switch member, a supporting bracket, a coil spring interposed between the supporting bracket and the head of the said movable switch member, a stop plate carried by the movable switch member to limit the downward movement of the switch member in the housing when the two switch members are in engagement, such movable switch member being in close proximity to the head of one of the rails whereby it will be engaged by the flange of one of the wheels of the train, an electric circuit having conductors connected to the said switch members, a signal element arranged adjacent the grade crossing at opposite sides of the said rails and including a signal element adapted to be electrically energized when the two switch elements are in engagement to close the circuit, each signal element including a casing having transparent panels, a light mounted in the casing and connected in the said circuit, each of the said panels being inscribed with an inscription to be observed by the drivers of approaching vehicles.

In testimony whereof I have affixed my signature in the presence of two witnesses.

JERRY E. WESOLOWSKI.
